(57) CLAIM

The ornamental design for a cushion, as shown and described.

DESCRIPTION

FIG. 1 is a front-left-top perspective view of a cushion, showing my new design;

FIG. 2 is a front elevational view thereof; the rear side being a mirror image thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front perspective view thereof, wherein the broken line portion of the disclosure is for illustrative purposes only and forms no part of the claimed design.
